LOCK AND MFG. CO., A CORPORATION OF IDAHO.

LOCK.

1,087,069.

Specification of Letters Patent.

Patented Feb. 10, 1914.

Application filed March 21, 1912. Serial No. 685,248.

To all whom it may concern:

Be it known that we, ALMA A. OLSON and GEORGE H. BLOOD, citizens of the United States, and residents of Preston, Idaho, have invented certain new and useful Improvements in Locks, of which the following is a specification.

Our invention relates to an improved form of lock and key therefor.

10 A principal object of the invention is to make it extremely difficult and practically impossible to pick the lock or to operate it without the special key provided for it.

Another object is to provide the bolt with 15 a plurality of levers, all of which must be operated in order to shoot the bolt.

A further object is to construct the bolt and levers so that it is impossible to move the bolt unless the levers are first moved 20

a certain distance, and so that it is also impossible to move the bolt if the levers are moved too far.

25 A further object is to provide a special key with a form of expandible bit or bits which operates simply and is easy to manufacture and to construct the lock so that it coöperates with this form of key-bit.

30 A further object is to construct the lock and key so that it is easy to make slight changes in individual products so that a certain key will only actuate its own particular lock.

35 We will now describe an exemplifying form of the invention as shown in the accompanying drawing. It is to be understood that the invention is capable of embodiment in many other forms.

Figure 1 is an elevation of a lock with the cover plate removed. Fig. 2 is a vertical section on the plane of the keyhole. Fig. 3 is a fragmentary view of the bolt-reverse and key, showing the levers in the released position and the bolt ready to be shot by the key. Fig. 4 is a similar view 40 with one of the levers removed to clearly show the remaining lever in proper position to release the bolt. Fig. 5 is a similar view showing the lever in position to hold the bolt in its extended or locked position. Fig. 45 50 6 is a detail enlarged view of the key, a part being shown in section.

Reference character 1 designates the bolt provided with slot 2 embracing the fixed pin 3. The bolt also has the arc-like segment 4 and notch 5 for engagement by the fixed part of the key-bit. One or more levers 6

are provided. Usually there are two, one on each side of the bolt as shown. The levers are pivoted on the pin 3. The lever springs may differ greatly in form and arrangement but, in the convenient form of the invention, they are simply supported by a stud 10 in the casing and have their active ends 11 engaging upon lugs 12 of the levers. The opposite ends of the springs 60 may be placed against the pin 13 in the casing, which may also support the latch spring 14, as shown. Near one end, the bolt is provided with notches 15, 16, and near the other end it is provided with notches 17, 18, separated by lug 19. Each of the levers has at 65 one end an inward projecting tooth 20 to co-operate with notches 15, 16, and at the other end a tooth 21 to co-operate with notches 17, 18.

70 It will now be evident that as best seen in Fig. 4, the bolt cannot be moved away from either its inner or outer position unless both of the levers are held in practically the exact position shown in Fig. 4 with 75 their teeth 20, 21, both out of register with the adjacent notches 14, 15 and 17, 18. Both of the levers being so held, the bolt may be shot in or out. If the levers are then 80 free to move under the influence of their springs, or if only one of them so moves, its tooth 21 will engage in notch 17 supposing the bolt is inward and in notch 18 supposing the bolt is outward, and in either 85 case the bolt cannot be shot until the lever is properly raised. At the same time, in raising the levers to permit the bolt to be shot, if either or both of them is moved too far, the tooth 20 will enter either notch 15 or notch 16, and prevent movement of the 90 bolt. It is exceedingly difficult and practically impossible, therefore, to pick this lock because without the key specially provided each of the levers must be manipulated by some wire or other implement 95 and held at exactly the proper position against the spring pressure and at the same time a third wire or other instrument must be properly manipulated to shoot the bolt. This complicated operation, it is evident, 100 is practically impossible, especially since the lock presents no outward evidence of being different from an ordinary lock and gives no indication as to how it should be manipulated. The difficulty of picking, it will be 105 evident, is increased by providing independent springs for the levers, but when it is

110

considered unnecessary to do this the construction may be somewhat simplified by connecting the active ends 11 of the lever springs in the obvious manner.

5 The special key provided to operate the lock comprises an ordinary shank 30 and bit 31, which may be varied greatly in shape, and also two movable bits 32 which in a simple and advantageous form of the invention consist simply of short round rods inserted in the holes in the outer portion of the bit and movably secured in position by the pressure of a spring 33 compressed between the two rods in a transverse chamber 10 or bore in the bit. In the casing on the bottom and on the cover are provided two cams 35 preferably of oval shape as shown, so that a comparatively straight portion 36 is provided to hold the movable bits in extended position as they engage the levers during the movement of the bolt.

When the key is inserted in the lock, the movable bits are in their inward position as shown in Fig. 1. As the key is revolved, the 25 inner ends of the bits strike the cam and are pushed out so that as the fixed bit approaches the bolt notch 5, the movable bits raise the ends of the levers and release the bolt and hold the levers in released position 30 until the bolt is shot. Fig. 3 shows the key midway in its movement with the movable bits resting upon the cam and holding the levers in released position and with the fixed bit engaging the bolt notch after having 35 moved the bolt half-way out. This movement is continued until the fixed bit approaches the bottom 40 of the casing adjacent to the key-hole. The outer ends of the movable bit then encounter the side or bottom 40 wall of the casing and are pushed in again until they take the position shown in Fig. 1, whereupon the key may be removed from the lock and is ready for re-insertion to withdraw the bolt. It will be evident 45 that the movable bits are made just the proper length to properly engage the cam and at the same time to move the levers to the exact free position, and it will also be evident that by slightly changing the shape 50 of one or both of the cams or the length of one of the movable bits and correspondingly changing the shape or arrangement of the corresponding lever, the lock may be made so that it can be opened only by the particular key designed for it.

Having described our invention, what we claim is:—

1. In a lock, the combination of a casing having a keyhole, a bolt, a lever-tumbler 60 therefor, a pivot for the lever-tumbler, the bolt and lever-tumbler being provided at each side of the pivot with complementary notches and projections whereby the bolt is released from the lever-tumbler when the

latter is moved a certain distance but is re-engaged by the lever-tumbler when the latter is moved more than said certain distance, a key, an extensible bit carried thereby, the bit being movable approximately at right angles to the key axis, a cam adjacent to the keyhole for engaging the inner end of said bit and throwing it out by the rotative movement of the key, the casing being constructed and arranged to engage the outer end of said bit and retract it to permit withdrawal of the key.

2. In a lock, the combination of a casing, a bolt therein, a pin passing through a slot in said bolt, bolt lever-tumblers, one on each side of said bolt and pivoted on said pin, the lever-tumblers being provided with projections at each side of said pin, and the bolt being provided with complementary notches for engagement by said projections in both the inward and outward positions of the bolt, the bolt being provided with a key socket and the lever-tumblers being provided with extensions adjacent to said socket, a key having two extensible bits for engaging said lever-tumbler extensions, and 80 cams carried by the casing adjacent to the keyhole acting upon rotary movement of the key to extend the bits and cause them to move the lever-tumblers to released position while the key engages the bolt socket to 95 shoot the bolt.

3. In a lock, the combination of a bolt, a plurality of co-operating retaining lever-tumblers, a spring for each lever-tumbler, a key having a plurality of expansible bits 100 and cams adjacent to the key-hole one for each bit, the cams, bits and lever-tumblers being relatively constructed so that in one rotation of the key the bits are first extended, then actuate the lever-tumblers to 105 release them while the bolt is shot, and the bits are then retracted to permit the key to be withdrawn.

4. In a lock, the combination of a casing having a keyhole, a plurality of cams carried by the casing adjacent to the keyhole, a bolt, a plurality of lever-tumblers therefor having means to engage the bolt except when moved to a certain free position, a key, and a plurality of extensible bits carried 110 by the key adapted to be severally engaged by said cams during the rotary movement of the key to extend said bits.

5. In a lock, the combination of a casing having a keyhole, a plurality of cams carried by the casing adjacent to the keyhole, a bolt, a plurality of lever-tumblers therefor having means to engage the bolt except when moved to a certain free position, a key, and a plurality of extensible bits carried 115 by the key adapted to be severally engaged by said cams during the rotary movement of the key to extend said bits, said bits

being adapted severally to raise the lever-tumblers each to its free position and then engage and shoot the bolt.

6. In a lock, the combination of a casing having a keyhole, a cam carried by the casing adjacent to said key-hole, a bolt, a lever-tumbler therefor, a key, a rigid bit carried by the key to engage the bolt, and an extensible bit carried by the key adapted to be engaged and extended by said cam so as to engage the lever-tumbler.

7. In a lock, the combination of a casing having a keyhole, a cam carried by the casing adjacent to the keyhole, a bolt, a lever-tumbler therefor having means to engage the bolt except when moved to a certain definite free position, a key, a rigid bit car-

ried by the key to engage the bolt, an extensible bit carried by the key and adapted to be engaged and extended by said cam and in turn to engage and raise the lever-tumbler, said cam being elongated in the direction of the movement of the bolt, the engagement faces of the lever-tumbler and of the cam being arranged substantially parallel to each other so that the lever-tumbler is raised and held in the same position throughout a large part of the rotation of the key.
